DISH-MOP.

No. 908,791.

specification of Letters Patent.

Patented Jan. 5, 1909.

Application filed September 18, 1908. Serial No. 453,571.

To all whom it may concern:

Be it known that I, CHARLES ALEXANDER MASON, a citizen of the United States, residing at Washington, in the District of Columbia, have invented certain new and useful improvements in Dish-Mops, of which the following is a specification.

This invention relates to mops and more particularly to mops for washing dishes and 10 kitchen utensils.

The dish mop in common use comprises a handle portion and a mop head of cotton or other soft material, said head being commonly secured to the handle by cords, wires, 15 or other wrappings. Dishes, plates and kitchen utensils of various kinds are sometimes difficult to cleanse with this form of mop, especially where such dishes or utensils have been permitted to remain for any 20 length of time with food or other matter therein which has adhered to the surface of the dishes or plates, or lodged in the corners of the utensils.

The object of this invention is to provide a 25 new and improved mop of this character which shall be so constructed as to thoroughly and effectively remove any adherent matter from plates, dishes, or culinary articles of any kind without sacrificing any 30 of the advantages of the mop as heretofore constructed.

With the above object in view this invention consists of a dish mop composed of the ordinary handle and the mop head of soft 35 material having secured to the end of the handle a dislodging device, as a brush or scraper, constructed and arranged to remove adherent material, and furthermore constructed to enter the corners of kitchen 40 utensils in such manner as to effectively scrape out such corners and remove therefrom material of any character that may have lodged therein. This dislodging device 45 is so arranged relatively to the soft material of the mop head as to be entirely inclosed by said material which extends substantially beyond such dislodging device so as to conceal the same. When in use the dislodging device 50 may be operated to remove material from the surface or corner of a dish or utensil, which material is instantly taken up and effectively swept out of the plate or utensil by the mop head, whereby the dislodging device and mop head combine to secure a 55 valuable result in this class of devices.

One of the advantages following from the

arrangement of the scraping or dislodging device within the body of the soft material of the mop, and so as to be completely inclosed thereby, is to strengthen or stiffen 60 such soft material and thereby render it more durable, as well as to increase the efficiency of the mop when used in the ordinary manner, that is, as a swab merely. These advantages would follow whether the 65 dislodging or scraping device was a blade of flexible material, as in one form of applicant's invention, or was in the form of a stiff bristle brush, though possibly to a greater 70 extent in the latter case.

Referring to the accompanying drawings, in which like characters of reference denote like parts throughout:—Figure 1 is a view showing a portion of a bucket, or kitchen utensil, with this invention operating to 75 cleanse a corner thereof. Fig. 2 is a vertical sectional view of the preferred form of my invention. Fig. 3 is a view of a modification, showing the mop head in vertical section and the inner end of the handle and dislodging device in elevation.

The numeral 1 represents a dish mop handle of well known construction, the same having thereon the usual groove or grooves at the end to afford means for securing the 85 cotton strands or other soft material 2 thereto, by a cord or wire as shown. At the inner end of the mop handle, under this invention, I preferably form a recess and locate in such recess a bunch of bristles 3, which in practice 90 will be made to project from the end of the mop handle a proper distance, as will be determined by experiment. Referring to Fig. 2 of the drawing, this construction will appear very clearly, and it will be seen from 95 such view that the mop head 2 completely surrounds and conceals within it the bristles 3.

In operation this mop is used in the same manner as other dish mops, and when any material is found which adheres to the surface of the article being washed so as not to be removable by the mop head 2, a slight additional pressure upon the handle will bring the removing device 3 into contact with the substance whereby the same may be scraped or brushed from the surface of the utensil. In the operation of removing substances with this device the soft material 2 cooperates with the remover or scraper 3, as, when the substance has been dislodged, or partially 105 dislodged by the scraper 3, the soft material 2 acts to wipe or swab the same from the sur-

face of the utensil and remove it entirely therefrom.

In the hands of a skilful operator it has been found that this mop may be so manipulated that the head 2 and removing device 3 are alternately brought into operation upon different portions of the utensil as the condition of such utensil calls for their respective uses, and that with a very little practice food or other adherent material may be stripped 10 from the surface and the utensil cleansed in a very effective manner.

In Fig. 3 the removing device is in the form of a scraping blade 37, located precisely 15 in the same relation to the mop head 2 as the brush 3 shown in Figs. 1 and 2. In use, the construction shown in Fig. 3 is manipulated in substantially the same manner as in the preferred construction.

20 While I have shown two forms of removing devices to be associated with a mop in the

manner and for the purposes described herein, it is to be understood that this invention is not limited to any particular form of removing device.

Having thus described my invention, what I claim as new and desire to secure by Letters Patent is:—

A mop comprising a handle provided at its end with a recess, a scraping device within 30 said recess and projecting beyond the end of the handle and a body of flexible mop material secured to the end of the handle and extending a substantial distance beyond the scraping device whereby to completely conceal and infold the latter.

35 In testimony whereof I affix my signature in presence of two witnesses.

CHARLES ALEXANDER MASON.
